UNITED STATES PATENT OFFICE.

DUNCAN GRAHAM MEIKLEREID, OF LEE, ENGLAND, ASSIGNOR TO THE BABCOCK & WILCOX COMPANY, OF BAYONNE, NEW JERSEY, A CORPORATION OF NEW JERSEY.

CHAIN GRATE.

Application filed May 13, 1919. Serial No. 296,822.

To all whom it may concern:

Be it known that I, DUNCAN GRAHAM MEIKLEREID, a subject of the King of Great Britain, residing at 98 Burnt Ash Hill, Lee, 5 county of Kent, England, have invented certain new and useful Improvements in Chain Grates, of which the following is a specification.

This invention relates to chain grates and 10 has for its primary object to provide improved constructions of grate bar links such that with the combination of links assembled and enclosed at top and bottom the escape of air between the links and between 15 the top and bottom closures when the mechanical stoker is working with air under pressure is largely prevented. A further object is to provide a construction of outside 20 grate bar link such that a sufficient air seal may be maintained between the outside grate bar links and the carriage frame of the mechanical stoker.

The invention also relates to the particular construction of grate links illustrated 25 in the accompanying drawings.

My invention will best be understood by reference to the accompanying drawing, in which like reference characters indicate like parts, and in which Figure 1 is a side view 30 with parts in section of a chain grate stoker embodying my invention; Fig. 2 is a plan view of a portion thereof; Fig. 3 is a plan view illustrating a central link, an outer link, and an intermediate link, in assembled 35 position; Fig. 4 is a side elevation of part shown in Fig. 3 as viewed from the right; Fig. 5 is a side elevation of a central link; Fig. 6 is a vertical section through the central link on the line 6—6 of Fig. 5; Fig. 7 40 is a vertical section through an outer link; Fig. 8 is a side elevation of an intermediate link; Fig. 9 is an end elevation of the intermediate link; Fig. 10 is a vertical section 45 of the intermediate link on the line 10—10 of Fig. 8; Fig. 11 is a plan view of a slightly modified form of intermediate link, Fig. 50 12 shows diagrammatically the arrangement of the illustrated form of top and bottom covering plates, and Fig. 13 is a vertical section on line 13—13 of Fig. 2.

Referring now to the drawings, the grate is made up of a number of connecting pins 10 and links of three different forms, most of the links being the central links 11. As

shown best in Figure 2, these central links 55 have reduced end portions which permit them to be closely spaced along each of the pins 10, and a widened surface portion at the middle to fill up the larger part of the space between the pins. Each of the central links 11 is provided with the widened surface portion 12 and a narrower surface portion 13, this latter being substantially the same width as the eyes or bearings 14 through which the pins 10 pass. Beneath 60 the surface portions 12 and 13 is a vertical supporting web 15 which may be extended at each end beyond the eyes 14, as shown at 16 and 17, the surface portion extending beyond the web as shown. Preferably, each 65 side of the surface portions 12 and 13 is ribbed, as shown in Figures 3 and 5.

Beneath the wide surface portion 12 and extending to the bottom of the web 15 is a vertical rib 18 on each side of the link 70 extending flush with the surface portion, for a purpose to be more fully hereinafter referred to.

The arrangement of the central links assembled in the chain, is best shown in Figure 2, in which it will be seen that the widened portions 12 of adjacent links come relatively close together and that the narrowed portions 13 are spaced apart a sufficient distance to allow the corresponding 80 narrow portion 13 of a link on the other side of the connecting pin to be placed therebetween. This arrangement provides for a substantial filling up of the surface of the chain except for the narrow openings between the links, which openings are further augmented by the diagonal air channels extending across the sides of the surface portions 12 and 13 as illustrated in Figs. 5 85 and 6. It will be also noted that the vertical 90 ribs 18 on adjacent links come edge to edge so as to form a relatively closed rib extending transversely of the grate. It will also be observed that at the connecting pins 95 the eyes 14, by reason of their close assembly on the pins correspondingly, provide a relatively continuous member longitudinally of the pins.

In order to seal the chain between the stoker frame and the grate I provide marginal links 20 which in general are of a shape similar to that of the central links 11; that is, each marginal link has reduced por-

tions through which the connecting pins pass and a widened surface portion to fill up the space which would otherwise be present, these end reduced surface portions being indicated respectively at 21 and 22 and the widened portions at 23. The surface portions of the link are supported by a vertical supporting web 24 and suitable bosses 25 thereon through which bearings are provided for the connecting pins. On the outer side of the link is a flange 26 extending laterally along the lower edge of the web 24 and partly around the extremity of the link, as shown in Figure 4. Said laterally extending flanges are preferably relatively thin and extend beneath the link centers as shown, the space between the ends of said flanges on adjacent links being relatively small and the ends of said flanges being curved to maintain such space substantially constant during the entire travel of the chain. As shown best in Figure 2, this flange is arranged to come closely to the frame of the stoker A.

In order to fill up the space which would otherwise occur between the marginal links, I provide an intermediate link 28 which has reduced surface end portions 29 and a widened middle portion 30. This link is also provided with eyes or bosses 31 through which the connecting pins extend and a supporting web 32 beneath the surface. On one side only of the intermediate link I provide a vertical rib 33 which cooperates, as shown in Figure 2, with the corresponding rib on the central link 11. The intermediate link 28^a illustrated in Figure 11 differs from that shown in Figures 8, 9 and 10 only in having diagonally extending air channels on both sides rather than one side only, as shown in the latter figures.

Referring now to Figure 1 which shows an illustrative form of chain grate stoker provided with my novel connecting links, A represents the side frame of the stoker with which the flanges 26 of the outside links co-operate, B is the hopper, and C indicates air seals for the stoker, disposed between the upper and lower runs of the chain grate, air under pressure being supplied through the openings D.

It will be noted that in order to save weight, I have cut away the lower portion of each link. If this were done without a special arrangement of links, and the stoker were operated with a forced blast, there would be an undue amount of air leakage between the chain grate and any closure that might be placed beneath the links of the grate. This air leakage would naturally occur between the runs of the chain and the air would pass along the chain in the direction of the chain travel. By providing the special air seal in connection with the links which I have devised, as shown in Fig. 1,

the air leakage between a closure at the bottom of the links and the chain grate is avoided.

It will thus be seen that the transverse rib formed by the ribs 18 of the central links and by the ribs 33 of the intermediate links extends between the webs 32 of the intermediate links on either side of the chain across the major portion of the chain. The portion of the chain without the webs 32 of the intermediate links is sealed by the engagement of the bosses 31 on the intermediate links engaging the corresponding bosses 25 on the outer links and the bosses 14 on the central links. These bosses form a substantially continuous partition or rib extending from the web 32 of the intermediate link to the margin of the chain. The space between each unbroken rib is the same as the distance between the pins which engage the links. It will be seen by referring to the semi-diagrammatic Fig. 12 that if the plate E is long enough to span the space between two of the ribs, there will always be one of the ribs above the plate, and that an air seal is thereby provided. The arrangement therefore results in a chain of relatively light weight in which the lower portion of the chain can be sealed against air leakage.

I also provide a seal F at the top of the grate and beneath the hopper B. The object of this seal is to prevent the air blast from passing upward between the links directly at the rear of the hopper B and through the fuel in the hopper. The air which passes up through the fuel in the hopper leads to a wasteful process and in some instances may cause trouble through igniting the coal in the hopper.

It will be seen, therefore, that by my novel arrangement I have provided first a relatively light chain in which substantially all of the surface is filled up and second, an arrangement by which, although the links themselves are reduced in weight, there will be little or no air lost by leakage over the air seal through the chain itself and that substantially all of the air will be obliged to find its passage vertically through the chain and into the bed of coal.

What I claim and desire to secure by Letters Patent of the United States is:—

1. A chain grate comprising links pivotally connected together and each formed with a relatively wide surface portion and a relatively narrow supporting web, said webs being provided at parts intermediate vertical planes through the pivotal points of said links with laterally extending ribs limited in extent by the edges of said surface portions and forming a practically continuous transverse rib on the inside of the chain and across the major portion thereof.

2. A chain grate comprising links pivotally

- ly connected together and each formed with a relatively wide surface portion and a relatively narrow supporting web, said webs being provided at parts intermediate vertical 5 planes through the pivotal points of said links with laterally extending ribs limited in extent by the edges of said surface portions and forming a practically continuous transverse rib on the inside of the chain and 10 across the major portion thereof, and an air seal or closure disposed adjacent to the inner surface of the chain and of sufficient length to span the space between two successive transverse ribs of the chain.
- 15 3. A chain grate composed of connecting pins and links pivotally connected together by said pins and closely arranged thereon, each link having a relatively wide surface portion and a relatively narrow supporting 20 web, and an air seal located between the upper and lower runs of the chain and adjacent thereto, certain of said links being provided at parts intermediate vertical planes through the pivotal points of said 25 links with laterally extending ribs limited in extent by the edges of said surface portions and forming a practically continuous rib on the inside of the chain and across the major portion thereof, cooperating with 30 said seal to limit the flow of air through the links of said grate and longitudinally thereof.
4. A chain grate comprising connecting pins and links pivotally connected together 35 by said pins and closely arranged thereon, a frame for the stoker adjacent to said chain, each link having a relatively wide surface portion and a relatively narrow supporting web, said supporting webs being provided 40 at parts intermediate vertical planes through the pivotal points of said links with laterally extending ribs limited in extent by the edges of said surface portions, the ribs of the various links located side by side forming 45 a practically continuous transverse web on the inside of the chain and across the major portion thereof, and an air seal located between the two runs of the chain and adjacent thereto, the outer links being provided with lateral flanges extending close to 50 the frame of the stoker.
5. A chain grate stoker comprising side frames, central links each formed with vertical ribs one on each side, marginal links each 55 formed on one side with a curved flange extending along the lower edge and a part of each extremity of the link, complementary or intermediate links each formed with a vertical rib on one side only, and pins connecting 60 said links to form a chain grate with a substantially continuous barrier to the flow of air through said links parallel to the run of the chain, said curved flanges forming a barrier to the flow of air between the chain and 65 the side frames of the stoker.
6. A link for a chain grate stoker having openings at its ends for receiving connecting pins and comprising a web, a surface portion extending laterally beyond said web and wider at its middle portion than at its ends, 70 and a vertical rib on said web at a part intermediate said openings, the outer side of which rib is substantially parallel with said web and extends flush with said widened surface portion and substantially to the 75 lower side of said link.
7. A chain grate comprising links each formed with a relatively wide surface portion and a relatively narrow supporting web, said webs being provided with laterally extending ribs forming a practically continuous transverse rib on the inside of the chain, a hopper for the chain grate, a closure plate disposed at the bottom of the hopper and adjacent the chain for preventing air from 80 passing through the chain grate and into the hopper, and an air seal or closure disposed adjacent to the inner surface of the chain grate beneath said closure plate and of sufficient length to span the space between 85 two successive transverse ribs of the chain.
8. A link for a chain grate stoker having a relatively wide surface portion and a relatively narrow supporting web, the surface portion being relatively wide at its intermediate portion and relatively narrow at its ends, the narrow ends being provided with 90 openings for the reception of supporting rods, said web being provided intermediate said openings with a rib extending laterally with its outer edge flush with the edge of the surface portion of the link.
9. In an endless chain grate stoker, a frame marginal links having laterally extending, 95 relatively thin flanges with the outer edges thereof adjacent said frame and said flanges extending beneath the link pivot centers, the spaces between the ends of said flanges on adjacent links being relatively small and the ends of said flanges being curved to maintain such spaces substantially constant during the entire travel of the chain.
10. A chain grate comprising central, intermediate and marginal links, each provided with a comparatively wide surface portion and comparatively thin vertical longitudinal webs, each intermediate link being provided with a rib on one side only of its web extending laterally substantially flush with the surface portion, each central link being provided on each side of its web with a rib extending laterally substantially flush with its surface portion, the ribs of side by side central and intermediate links forming 110 a substantially continuous transverse rib extending transversely of the chain from the web of an intermediate link on one side to the web of an intermediate link on the other side, said marginal links being provided with laterally extending flanges forming a 115
- 120
- 125
- 129

barrier to the flow of air between the chain and the side frames of the stoker.

11. A chain grate comprising central, intermediate and marginal links, each provided with an extended surface portion and vertical longitudinal webs, each intermediate link being provided with a rib on one side only of its web extending laterally substantially flush with the surface portion, 5 each central link being provided on each side of its web with a rib extending laterally substantially flush with its surface portion, the ribs of side by side central and intermediate links forming a substantially continuous transverse rib extending transversely of the chain from the web of an intermediate link on one side to the web of an intermediate link on the other side, and means 10 forming transverse partitions between the webs of said intermediate links and the margins of the chain, said marginal links being provided with laterally extending flanges forming a barrier to the flow of air between the chain and the side frames of 15 the stoker.

12. A chain grate comprising central, in-

termediate and marginal links, each provided with an extended surface portion and a vertical longitudinal web, each intermediate link being provided with a rib on one side only of its web extending laterally substantially flush with the surface portion, each central link being provided on each side of its web with a rib extending laterally substantially flush with its surface portion, 30 the ribs of side by side central and intermediate links forming a substantially continuous transverse rib extending transversely of the chain from the web of an intermediate link on one side to the web of an intermediate link on the other side, said marginal links being provided with laterally extending flanges forming a barrier to the flow of air between the chain and the side frames of the stoker and a seal located between the runs of the chain and comprising engaging members spanning the distance between successive ribs or partitions.

In testimony whereof I have hereunto signed my name.

DUNCAN GRAHAM MEIKLEREID.
